(57) **CLAIM**

We claim the ornamental design for a refrigerator, as shown and described.

DESCRIPTION

FIG. 1 is a front perspective view in accordance to a first embodiment of a refrigerator showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 1;

FIG. 9 is a front right-side perspective view in accordance to a second embodiment of a refrigerator showing our new design;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof;

FIG. 16 is a front left-side perspective view thereof;

FIG. 17 is an enlarged view of the encircled portion in FIG. 16;

FIG. 18 is an enlarged view of the encircled portion in FIG. 10;

FIG. 19 is a front right-side perspective view in accordance to a third embodiment of a refrigerator showing our new design;

(Continued)

FIG. 20 is a front view thereof;
 FIG. 21 is a rear view thereof;
 FIG. 22 is a left-side view thereof;
 FIG. 23 is a right-side view thereof;
 FIG. 24 is a top view thereof;
 FIG. 25 is a bottom view thereof;
 FIG. 26 is a front left-side perspective view thereof;
 FIG. 27 is an enlarged view of the encircled portion in FIG. 19; and,
 FIG. 28 is an enlarged view of the encircled portion in FIG. 20.
 The evenly-dashed broken lines in the figures depict portions of the refrigerator which form no part of the claimed design.
 The dot-dot-dash broken lines encircling portions of the claimed design that are illustrated in enlargements form no part of the claimed design.
